UNITED STATES PATENT OFFICE.

JOHN LUDWIG, OF ERIE, COLORADO.

DESIGN FOR A HOLDER FOR TOOTHPICKS, &c.

SPECIFICATION forming part of Design No. 23,150, dated March 27, 1894.

Application filed February 27, 1894. Serial No. 501,726. Term of patent 14 years.

To all whom it may concern:

Be it known that I, JOHN LUDWIG, a citizen of the United States, residing at Erie, in the county of Weld and State of Colorado, have 5 invented a certain new and useful Design for Toothpick-Holders, of which the following is a specification.

My invention has reference to a new design for a holder or receptacle for matches, toothpicks, or similar articles.

In the drawings hereunto annexed Figure 1 represents my holder in perspective; and Fig. 2 is a vertical longitudinal sectional view.

A designates the base, which is oblong in 5 its general form, its ends being tapered and shaped into handles or projections *a a*. The base is made to contain a drawer B, one end of which forms one end of the base and one

of the handles *a*. Mounted upon the base is the holder or receptacle proper, designated ²⁰ by C, and this portion is the general shape or contour of a shoe or clog. Near its rear end it is provided with a curved support D. The drawer is designed to hold a supply of matches or toothpicks;—and the shoe, those desired ²⁵ for immediate use, the curved support holding the ends elevated in a convenient position.

What I claim is—

The design for a holder or receptacle herein shown and described. ³⁰

In witness whereof I hereunto set my hand in the presence of two witnesses.

JOHN LUDWIG.
